[57] CLAIM

The ornamental design for a toy for dog or similar article, as shown and described.

DESCRIPTION

FIG. 1 is a top plan view of a toy for dog or similar article showing my new design, a bottom view being a mirror image thereof;

FIG. 2 is a side elevational view of the toy for dog or similar article thereof, the opposite side being a mirror image;

FIG. 3 is a front elevational view of the toy for dog or similar article thereof; and,

FIG. 4 is a rear elevational view of the toy for dog or similar article thereof.

FIG. 1

FIG. 2

FIG. 4
